METHOD FOR CUTTING GARMENTS

Adorján Ernö Szabó, Budapest, Hungary; vested
in the Alien Property CustodianApplication March 16, 1940, Serial No. 324,237
In Hungary March 18, 1939

1 Claim. (Cl. 33—17)

In the methods of cutting garments as employed up to now it was necessary to make use of the figures of proportion of an idealised type of body. As however, in reality it is not possible to find two equal human bodies and tailoring was rendered difficult by various combinations difficult to detect of different kinds of physical alterations of a greater or smaller extent resulting in greater or smaller deviations from the idealised type, the invention is based on the consideration that as against the uncertain methods employed up to now, it is necessary to make extended use of anatomical considerations. The invention is based on the recognition of the fact that a correct cutting process can only be obtained by paying attention to the following points:

I. It is necessary to measure the specific individual carriage of body in such a manner as to render the dimensions obtained independent of the involuntary movements, such as occur also during the process of taking measures, of the shoulders and arms and so as to offer a safe basis for the piece of work to be cut.

II. The proportion of width between the front and back part of the trunk should be ascertained.

III. Up to now no reliable method existed for satisfying the preceding two paragraphs, but as the method according to the invention to be described below solves both problems, this will at the same time also solve for the first time the problem of the "front neck point" (the point of intersection of the shoulder line and of the collar seam line), which question had been unsolved since the beginnings of the tailor's industry, because as the so-called "equilibrium point" of the front part of the coat this point was most indefinite.

IV. The well-known method of measurement of the carriage of the shoulders (the employment of which up-to-now has owing to the unsolved condition of the other more important problems not given good results in practice) will now, as an amplifying factor, again play a part, its present function being that (the said three problems being solved) it should be an accessory means of the method according to the invention based on trunk carriage, and is intended to enable suits of perfect cutting to be made, possibly even without trying them on. The invention will be described below in the first place in connection with men's coats.

The method according to the invention is based mainly on the combination of the following three reliable data, which are anatomically char-

acteristic for the trunk carriage of the person in question and are independent of the accessory movements performed by the body during trial:

1. The base line around the waist,
2. The dimension (side-waist length), starting from one of the lower cervical vertebrae, preferably from the seventh cervical vertebrae, from the so-called neck centre and extending through the point of intersection of the shoulder line and 10 of the collar line to that section of the base line as is situated in the side part; this dimension extends preferably along a vertical line forming the continuation of the arm pit front line,
3. The dimension (front waist length) extending 15 from the seventh neck vertebra likewise, through the point of intersection of the shoulder line and the collar line to the front centre point of the base line.

The front part of the coat has in most cases 20 the tendency that it should be of greater length than the side parts and this difference in length varies greatly according to the various individuals (for instance between $\frac{1}{4}$ inch and 3 inches). In respect of this difference of lengths which up to 25 now has not been recognized and instead of which very complicated manipulations and other unreliable methods were employed, the invention provides an anatomically defined uniform method.

- 30 One of the most important advantages of the method according to the invention is that it is the first method by which the practical and uniform carrying into effect of so-called correct-pattern cutting, mainly of correct-striped cutting 35 is for the first time rendered possible. Experiments have been carried on for a long time in view of eliminating the unpleasant absence of system regarding the stripes coming to be placed above the various parts of the body when cutting 40 garments from patterned and particularly striped material, but up to now it has not been possible to find a reliable uniform method of cutting in this respect. As against this, the method, based on anatomical recognitions, according to 45 the invention and particularly the defined neck peak point resulting from it (the point of intersection of the shoulder line and of the collar line) also solves the question of correct-striped cutting. The main reason of the failure to 50 achieve satisfactory results up to now was that on the parts cut on the basis of unreliable data, e. g. on the shoulder parts there resulted a varying density of the stripes depending on the cutting, and an incorrect mating of the stripes. This circumstance was complicated still further by the

incorrect lengthening of the front shoulder seam line and often by the cutting directed from the neckline towards the breast and the frontal condensation (working-in) the intention of which was to follow the convexity of the body.

On the drawings a mode shown by way of example of carrying the cutting process according to the invention into effect and an embodiment shown by way of example of each of the means according to the invention are illustrated diagrammatically.

Fig. 1 shows in front view the taking of the measure situated in the line of continuation of the arm pit front-line.

Fig. 2 is a back view corresponding to Fig. 1 and at the same time also to Fig. 3.

Fig. 3 shows in front view the taking of the measure leading to the front centre point of the base line around the waist.

Fig. 4 illustrates in diagrammatical front view, in perspective, a further embodiment for determining any deviation from the standard proportion as between breast and back width, of the method according to the invention.

Figs. 5 and 5a are examples of cutting patterns prepared in accordance with the method according to the invention.

Figs. 6 to 10 and Figs. 6a to 10a, respectively, illustrate the drawbacks presenting themselves in the case of striped clothing materials, of the cutting methods employed up to now, and the advantages of the correct-striped cutting according to the invention, shown in parallel.

Fig. 11 shows two examples of the drawing of the trousers binding line.

Fig. 12 is a view drawn to a smaller scale, of the universal curve ruler according to a further development of the invention which ruler is equally suitable for drawing all lines of greater or smaller radius of curvature occurring in the cutting of clothes.

According to Fig. 1 a band or cord I made of any desired flexible material is placed horizontally around the waist and thus a definite base line for exactly measuring the carriage of the trunk is obtained for the taking of measures, which line will at the same time serve as the slimming (winging) line of the completed coat. Easing measurements on this line the first datum of taking measures is obtained according to Figs. 1 and 2 in such a manner that the end of the usual flexible measuring tape II is fitted to the anatomically defined neck centre point III (seventh cervical vertebra) and the measuring tape II is led through the point of intersection IV of the shoulder line and collar line i. e. through the so-called neck peak in a vertical direction coinciding with the front arm pit line to the base line I and reading the dimension of the measuring tape at its point of meeting V with the base line I.

According to Fig. 3 the following dimension is obtained in such a manner that the measuring tape II is started likewise from the point III according to Fig. 2 led through the neck peak IV to the centre of the front part of the base line I i. e. to its "front centre" VI and reading the dimension at this point.

Fig. 4 illustrates the exact determination according to the invention of the half back width representing an important datum for cutting. In this respect another feature of the invention consists, in contradistinction from previous unreliable methods, in proceeding in such a manner as to place a lath VII, in approximately hori-

zontal position into each arm pit; according to practical observation these laths will in case of a tight carriage of the body diverge in front, whereas in case of a bent carriage of the body 5 they will mutually converge. On the basis of this observed relation the measuring tape II is brought into a horizontal straight position in contact with the centre of the thorax and a distance between the two laths VII is measured; a 10 similar procedure is adopted in the back side also i. e. the distance between the two laths is also measured in that position of the measuring tape when the latter is in contact with the centre of the back. The usual half back width dimension should be increased or diminished by one-quarter 15 of the difference between the two data, according to whether the body carriage is bent or tight.

Fig. 5 is an example of a cutting pattern prepared in accordance with the method according to the invention, in the first place on the basis of the data now described, and also making use of the other usual data, suitable for the case in which the coat is cut with a special side part instead of with a front part cut in one. The method of designing this cutting pattern is in its main parts the following:

A drawing of the back part of the coat is prepared in such a manner that the horizontal arm-pit line 3—8, the waistline 4—19 and the bottom edge line 5—21 are extended for the front part.

3—7=half back width + $\frac{3}{8}$ in.
3—8=half back width + 5 in.
7—9=0.1 times the breast width
9—11=2 inches
11—12=0.05 times the breast width + $\frac{3}{8}$ in.

From the points 8 and 12 obtained, the lines 12—12a, and 8—16 (the latter is the so-called 40 breast centre line) are drawn perpendicularly to line 3—8.

The point A is obtained by adding $1\frac{1}{2}$ in. to the distance 8—12 and measuring back this total along the line 19—4 from the point 19 obtained 45 by means of the line 8—16. The halving point of this distance 19—A is the point 18, from which a perpendicular is drawn upwards and downwards. Thus there is obtained the point 14 on the line 8—12; from this point, 2 inches are measured 50 downwards to point 17, which is the end point of the breast seam.

In accordance with the invention the dimension (side waist length) obtained according to Fig. 1 is taken into account on the cutting pattern, 55 after deduction of the back neck width 1—10, in such a manner that the continuation of the line 18—14 is intersected with this distance from the point A mentioned above, thereby obtaining the point B. Further, the front centre line 8—16 60 of the trunk is intersected by the dimension (front waist length) obtained according to Fig. 3, after the deduction of the back neck width likewise, but starting this time from point B; it is thus obtained the point C. It is thus that 65 the theoretical triangle A—B—C, characteristic for the invention, marked by staggered lines, is produced in the cutting pattern; it is only the angle points of this triangle that are of importance and it is not necessary to trace its two scales on the cutting pattern.

In accordance herewith the part 19—A of the base line around the waist will be replaced by the oblique line C—A. It is the extent of this obliquity, i. e. the magnitude of the difference 75 between the side waist length and the front waist

length that defines according to the invention the necessary magnitude of front lengthening mentioned in the introductory part of this specification, as well as of the corresponding re-shortening of the side, the other implications whereof are described below.

C—20 height of pocket, about 4 inches.

Perpendiculars are drawn in the downward direction from the point A on the line 4—19, and from the point 20 on the line 8—16. Similarly a perpendicular is drawn from the point B of the line B—15 until reaching the points 12 and b.

From the point 18a which owing to the fact of the line having become oblique has come to be placed in a lower position the line A—C is intersected with a distance of about $\frac{3}{4}$ inch, thus obtaining the point 18b (in the case of striped material this distance may vary from $\frac{1}{2}$ inch to $\frac{1}{4}$ inch).

The point 18b is connected with point 11, and further a parallel to the line 18a—15 is drawn from the point 18b until reaching the point 15a.

The distance 19—C is measured up from the point 22 until the point 22a, and further, one-third of this dimension is measured up from the point 15a until reaching the point 15b, which latter is connected with the point 22a slightly extended.

In order to supplement the taken-out part 15—15a plus $\frac{3}{8}$ in. is measured up on the continuation of the line 15b—22a, thus obtaining the point 22b.

Distance C—16=distance 4—5+ $\frac{3}{8}$ inch.

In order to make up for 22—22a, this distance is measured down from point 21 to point 21a, and connecting the latter with the point 16, the base line of the front part is obtained.

From the point 21 to the point 21b the distance 15—15a is measured.

From the point A $\frac{3}{8}$ in. is measured towards the right. The point 11a thus obtained is connected with the points 11 and 22b, following which the point 21b is connected with the point 22b, and the point 9 with 22b. From the point 23 thus obtained up to the point 23a there is measured 0.1 times the belly width plus $\frac{1}{2}$ inch.

The half hip width is in a manner per se known (with the addition of the necessary surplus for "comfort") measured over and thus point 24 is obtained.

Measuring the distance 7c—18b on the line 12a—B there is obtained the point b which is the so-called neck peak point of the front part.

As appears from what has been said above, the point 7 results from measuring up the back width, and it is joining on to this point indirectly (by means of the point 9, 11) the place of the front armpit line (point 12), as well as the breast width of the front part. It is evident that as a result of this method of designing the cutting pattern the breast width of the front part will result in adverse proportion to the task width (i. e. the wider the back, the more narrow will be the breast) as indeed in accordance with the anatomical shape of the body and as accordingly required for correct cutting.

On the line 4a—A—C it may be checked in the usual manner the half belly width to which in addition to the parts according to the sewing-in a surplus for comfort of 2 cm. is added. In case the belly width is greater the wanting quantity is added proportionately distributed at the points C, 18b and 11a, and in accordance herewith the boundary lines are traced more outwardly, as will be described below with reference to Fig. 5a.

Moreover there should be drawn from the breast centre line 8—C—16, adding to it the usual "transition"—wherewith also the buttoning line 25—26 is obtained—in the usual manner likewise, but preferably by making use of the curved ruler, to be described below, according to the invention, starting the point b, the neck cutting line of the front part and the boundary lines of the front part as well as all curved boundary lines, all of them without exception with the aid of the curved ruler according to the invention.

Notably, 1a—10a back-neck line; 10a—7a back-shoulder line; 7a—7b back-armpit line; from 7b it is to be measured forward 1 cm. (point 7d), from here until to point 9 and continuing from point 11 to point 12a the front armpit line is traced; starting slightly below the point 12a the front shoulder line is traced in the manner shown on the figure through the point B to slightly above the point b; 7b—23a—24 is the seam line of the lateral part.

Substantial differences may occur as between the front waist length and the side waist length. Such differences present themselves particularly in the case of bodies whose bellies are pushed forward, but they may also arise in the case of tight breast carriage, which can be determined from the usual breast and belly width as well as from the proportion of widths (Fig. 4) of the front and back part. If the difference between the front waist length and the side waist length is caused by the protruded belly and if this difference is greater than $1\frac{1}{2}$ inches, the distance 19—C should nevertheless not be assumed at a greater figure than $1\frac{1}{2}$ inches, but the residue surplus should, as shown on Fig. 5a, be measured outside along the continuation of the line A—C up to C', in other words the point C is (also in order to make up for the lack in width which will in such cases anyhow present itself when measuring over the waist width) brought forward; thereby, at the same time the point 16 is also transferred to the point 16'.

The point B likewise is carried backwards, by two-thirds of the same surplus, to B¹, or in other words the line 14—B made oblique (so as to become 14—B¹). Parallel to the last named line the line 12—12a will also lose its character of being perpendicular to the line 11—8, or in other words the point 12a will also become placed backwards in the same extent as point B, into the point 12¹a and in accordance herewith the point b will also come to be placed more backwards. Thus the side waist length is measured from the point A already on the line 14—B¹

which has become oblique, and it is in accordance herewith that the perpendicular 12a—B¹—b will also shape out. By means of this operation it has been ensured that the distance B—C has become increased in the necessary extent, or in other words that together with the triangle A, B, C the front of the coat has shaped out in a manner corresponding to the dimensions of trunk carriage. In this case the point 16 is brought still lower down on the line C—16 by one-third of the above difference, and it is the new broken line 8—C'—16'—following the direction of the actual carriage of the trunk—which is taken as the basis for measuring over the hip width. To the same line it is also added the necessary transition when making the external border line of the front part moderately convex in the usual manner.

Fig. 5a also illustrates at the points 11a—11'a and 18b—18b' the method of making up for the deficiency in belly width mentioned above in case of bodies with large bellies.

If the difference between the front waist length and the side waist length is only caused by the tight breast and if this difference exceeds 1½ inches (which occurs rather rarely in such cases) the distance 19—C is not taken greater than 1½ inches, but, dispensing with any advancing of the point C, only the point B is carried more backwards (see point B on Fig. 5a) until the symbolic triangle A, B, C satisfies the dimensions of the front waist length and of the side waist length in the described manner. Naturally if the line B—14 becomes oblique so as to be converted into the line B'—14, the points 12a and b will also become altered accordingly.

The method described is suitable for the production of drawings corresponding to every type of body. In case of accurate design based on correct measures and of expert execution the results will exceed by far all former practice.

The peculiarly individual character of the measures taken will render the results most individual even in case the maker of the cutting pattern has never seen the customer. This is a special advantage for large workshops where methods of mass production are employed and every piece goes from hand to hand excluding the possibility of individualised work.

In case it is desired to cut the front and side parts of a coat in one piece it is possible to follow the method described by putting together the two parts of pattern on the cloth in bringing point 22 (Fig. 5a) to cover 22b and point 21a to cover point 21b and by replacing the quantity taken out from the breast seam by a special insert in a way per se known.

The special advantages of the cutting method according to the invention and securing a much better fitting of the clothes to the body than hitherto obtained, quite independently, of course, of the material employed, assert themselves quite particularly with suits made of striped material because of the reasons given below. Before going into particulars it is helpful to explain with reference to Figures 6 to 10 and 6a to 10a the advantages of the method according to the invention when applied to striped material and in comparison to methods employed hitherto.

As may be seen on Fig. 6 on front view, with striped clothes cut according to the methods used up to now the stripes on the front part seem to be curved towards the neck. As against this, when using the new method according to the invention the stripes will, as appears from Fig. 6a, follow accurately the direction of the seam by which the sleeve is sewn on.

Figs. 7 and 8 illustrate the fact that the old methods result in disorderly striping on the back, the collar and the lapels. On the other hand, as is illustrated by Figures 7a and 8a, the method according to the invention enables continuous, correct striping to be obtained on the back, collar and lapels even in the case of materials having stripes situated at large mutual distances.

According to Fig. 9 the method employed up to now has not ensured the correct meeting of stripes at the seam of the shoulders, i. e., the striping was disorderly also on this place and a meeting of the stripes could not ensue, the less as according to the methods of cutting and handling employed up to now the striping of the shoulders on the front part was wider and that of the back part narrower as compared to the original striping of the material employed; even when some of the pairs of stripes happened to meet, these stripes formed very conspicuous an-

gles with one another. On the contrary, when employing the method according to the invention (Fig. 9a) the stripes are following the bend of the body along the shoulder part quite correctly and so they do not only flow one into the other but, at the same time, conserving the original width of striping of the cloth, they form plastic, smooth and pleasant curvatures that follow exactly the upper seam by which the sleeves are sewn-on.

Finally, as shown by Fig. 10, in case of breast sewing done on the front cut hitherto in one piece, there is in front of the pocket a curved stripe separated from the other stripes. As against this, the method according to the invention results in correct striping along the pockets as illustrated by Fig. 10a.

The described advantages as regards correctly striped cutting are achieved by the method according to the invention in consequence of its following peculiarities:

Up to now, as the very considerable fluctuations of the differences in length between front part and side parts of the coat could not be taken into consideration at the cutting, the front part of the coat was not "in equilibrium," it went asunder, i. e. it stood off in the neck region or it tended to draw up, thus causing creasing in the side parts. The restoration of equilibrium was attempted by the uncertain displacement of the neck top point, the breast part was worked-in and the shoulder seam line lengthened. All this resulted in the stripes becoming curved according to Fig. 6. As against this, the method according to the invention results in a steady equilibrium of the coat and gives a definite neck top point on the cutting pattern—namely, when after making the cutting pattern according to Figs. 5 and 5a, the front parts cut out are seamed together, the point 22b being joined to point 22, and further when the breast convexity has been formed by ironing, not in front but from the armpits in the known way, and instead of the shoulder seam the curved neckline 23 below point b is lengthened and the breast part of the cloth is, in the usual way, arranged forward and the shoulder part backward, point b will finally come to be situated in the place of point B and a definite neck top point will be obtained. This and the parallelism between line 12—12a and the buttoning line 25—26 explain why correct striping on the front part according to Fig. 6a is obtained.

As illustrated in Fig. 7 it was usual up to now to stretch the lower edge of the collar, whilst the top line of the collar was shortened by adequate ironing resulting in the stripes becoming placed at wider intervals on the lower part and densified on the upper part of the collar, as a result whereof the stripes run together in the upward direction, and, besides, the striping on the back part did not coincide with that of the collar. As against this, the definite neck top point achieved by the method according to the invention enables one to establish a definite length of the collar thus making a correct meeting of collar striping and back striping, as shown by Fig. 7a, and at the same time, achieving the flowing together of collar stripes and lapel stripes in the sense of Fig. 8a. All that is required for this purpose is that the uppercloth of the collar (the upper collar) should be drawn along the line of the "underlying" part (lapel part) of the ironed-in lower collar, adding to it the usual "upstanding part" (or inner part), and that it

should be cut broader at the ends so as to facilitate the correct arrangement of the stripes. For tacking, if necessary, the cloth should be stretched obliquely by $\frac{1}{8}$ or $\frac{1}{4}$ inch. Contrary to the method according to Fig. 7 as employed up to now the outer back part of the upper collar is not stretched at all but only the inner back part. In case the inner cloth does not give properly way to the stretching, either the upstanding (or inner) part on the so-called upper collar must be made narrower or it is also possible to apply the well-known wedgeshaped filler.

The correct striping of the shoulder parts according to Fig. 9a is, first of all, a result of the definite neck top point and is also due to the fact that in using the method according to the invention (Fig. 5) the measure of the shoulder height gives automatically and according to the carriage of the customer the smaller or greater obliqueness of the back-shoulder-line (namely: in case of bent carriage the shoulder length is greater, with upright carriage smaller) and thus the more or less of "taking-in," necessary for a smooth fitting of the coat in compliance to the shape of the body and for a correct meeting of the stripes, results quite automatically. Contrary to the curved strips to be seen in Fig. 10 the correct striping along the pockets as shown by Fig. 10a is brought about by the equilibrium of the front part of the coat assured by the invention, as thus it is possible to pre-establish the direction of the pockets with full accuracy, to cut them out beforehand and, therefore, to take out from the cloth at the breast seam between points 15 and 15a the quantity corresponding to the stripe breadth, thus not only avoiding the stripes at the lower end point of the breast seam becoming curved but also achieving complete equality of stripe distances after sewing together.

The method according to the invention may be, in harmony to the cutting of the coat, also employed for the making of vestcoats and trousers, with the same effect. In particular, first of all, the operation carried out on the basis of base line and neck top point as described before will, in addition to the waistcoat, also ensure the correct cutting of the trousers and especially the right design of the upper, the so-called waist tie line of the trousers. Up to now no sufficiently reliable method existed for the cutting of the waist tie line of trousers, though it is the correct direction of that line that determines, in the first line, the correct "fall" of the trousers free of oblique creases. This too is achieved according to the invention by the determination of individual trunk carriage for cutting purposes as described above.

It is established by practical observation that with average, idealized types of body as taken for a basis by the cutting methods employed up to now and with regular carriage of body the front waist length exceeds the side waist length by about $\frac{3}{4}$ inch. But in reality the differences experienced are in the case of bodies with receding bellies smaller than $\frac{3}{4}$ inch, whilst in other cases the differences seem higher, especially in the case of bodies whose bellies are protruding as described in connection with Fig. 5a. In this direction a further feature of the invention is based on the observation that the protruding of the belly requires at the centre of the front part of the trousers, when compared to the normal, about as much of additional measure (in the upward direction and eventually also in the sense of forward displacement) as the dif-

ference between front waist length and side waist exceeds $\frac{3}{4}$ inch. In the case, for instance, that this difference amounts to 2 inches it will be necessary when drawing the front part of the trousers to displace the centre point C (centre point of the belly) upward and forward quite similarly and in harmony to the operation described in connection to Fig. 5a, when in the case of the coat the centre point marked C was displaced in the downward and forward direction. It is quite clear that in case of the aforesaid difference being less than $\frac{3}{4}$ inch the belly centre point is to be displaced in downward direction accordingly. Fig. 11 is an illustration of a partial design of the trousers tie line in two examples on one half of the cutting pattern of the front part of trousers. A is a point according to the above described cutting pattern (Figs. 5 and 5a) being in relation with the point B established with attention to the side waist length and C is the point obtained on the basis of the front waist length. In the above mentioned normal case ($\frac{3}{4}$ inch difference of lengths) the waist tie line of the front part of the trousers is given by the line A—C. In case of a body whose belly is receding point C is to be displaced downward to point C₁ in connection with and by the same method as the design of cutting pattern described above according to Figs. 5 and 5a, whilst in the opposite case, especially where there is a significant difference owing to considerable belly protrusion, C is to be displaced to C₂ i. e. considerably higher and forwards.

The ruler according to Fig. 12 as already mentioned above is suitable for the drawing of all curves of greater or smaller curvature as may be encountered in cutting for bodies of all sorts of measure. It is especially possible to draw the back-neck-line 10a—1a in the direction of the arrow x by placing the point d of the ruler on point 10a according to Fig. 5 and the back-shoulder-line 10a—7a, also in the direction of arrow x, by placing point e of the ruler on point 10a in the same way. By placing point j on the upper end point of line 28—b according to Fig. 5 and by help of part j—m of the ruler the shoulder line of the front part of the coat passing through point B of Fig. 5 is drawn. For the drawing of the back-armpit-line 1a—1b any part of that side of the ruler can be used which is marked f and possesses a large radius of curvature. The same side, marked by f, may be used for the drawing of the lapel-line 27, further of the arc below point 1b and of the side hip-line 23a—24. The front part of the armpit-line between points 12a and 11 is drawn by the help of parts h, i confining the inner cut g of the ruler, whilst part k serves for the design of the backward lower curvature of the armpit-line between points 9 and 7d. Further, it is by the help of this part k of the ruler that the neckline 28 is drawn. For the drawing of the initial part of the rounding-up below point 26 part m of the ruler should be used, and for the drawing of the continuation of the same, the part n confining the inner cut of the ruler. Finally, parts o, p of the ruler as well as part f will be used for the drawing of a pointed lapel of the front part, if such is wanted. In case of very full hips instead of part f of the ruler also part m may be used for drawing the upper part of line 23a—24. Further, part m of the ruler is suitable for drawing the elbow centre line of the coat sleeve and line n for the drawing of the so-called sleeveball (i. e. the upper, arched line of the coat

sleeve). Finally it is possible to use part *f* of the ruler for the design of the front seam line of the coat sleeve.

The ruler according to the invention joins into a close system all the curves to be met at the drawing of cutting patterns and which were up to now drawn by free hand rather uncertainly.

Having now fully described my invention, I claim:

In a method for cutting garments, particularly with patterned fabrics, and utilizing a predetermined base line about the waist, the combined steps, which consist in taking the longitudinal measurements of the front and side portions from the body of a subject for making the garment, between said base line and the point of

intersection of the shoulder and collar line as a definite neck top point, laying out on the cutting pattern a middle line passing through the neck top point by determining the proportion in width of the front and back portion of the garment while disposing two spaced laths at both sides of the trunk so as to protrude both in front and at the rear, and then measuring the convergence or divergence of said laths, and finally laying out these measurements upon a cutting pattern for designing the main parts of the latter, completing the cutting pattern by taking and applying the other usual measurements and then executing the cutting by means of the finished cutting pattern.
